UNITED STATES PATENT OFFICE.

ADOLF BACHNER, OF FRANKFORT-ON-THE-MAIN, GERMANY.

INCANDESCENT GAS-BURNER.

SPECIFICATION forming part of Letters Patent No. 738,512, dated September 8, 1903.

Application filed December 27, 1902. Serial No. 136,824. (No model.)

To all whom it may concern:

Be it known that I, ADOLF BACHNER, a subject of the Emperor of Russia, and a resident of Frankfort-on-the-Main, in the Empire of Germany, have invented certain new and useful Improvements in Incandescent Gas-Burners, of which the following is a specification.

Many attempts have been made heretofore to construct incandescent gas-burners which have the appearance of burning downward and which are generally known as the "inverted" type. They have, however, met with comparatively little success, because the downward stream of mixed gas and air has hitherto been unable to entirely envelop the mantle, and thereby render the whole of it incandescent when the gas was ignited.

This invention relates to a lamp for incandescent gas-lighting, and has for its object to provide a lamp which presents the appearance of burning downward and which resembles an electric lamp and to provide means whereby the mixture of gas and air is directed against the sides of the incandescent mantle, so as to completely envelop the same; and for this purpose the invention consists of an incandescent gas-burner comprising a supply-tube, a gas and air mixing chamber, a tubular support at one end of the mixing-chamber for supporting the incandescent mantle, and a baffle-plate supported at the lower end of the mantle for deflecting the mixture of gas and air against the sides of the mantle, as will be more fully described hereinafter and finally pointed out in the claims.

In the accompanying drawings, Figure 1 is a vertical central section of an incandescent gas-lamp embodying my improvement. Fig. 2 is a section on line A B of Fig. 1. Fig. 3 is an elevation, partly in section, of a modification adapted as a wall-bracket. Fig. 4 is an elevation, partly in section, of another modification, in which a chain support is used; and Fig. 5 shows a detail of the chain support shown in Fig. 4.

Similar letters of reference indicate corresponding parts.

Referring to the drawings, *a* represents the supply-tube through which gas enters to the nozzle *b*, from which it passes into the mixing-chamber *c*, while the air required for insuring a good mixture enters through the orifices *d*.

The mixing-chamber terminates in a tube *f*, to the lower end of which a tubular support *g* is attached by means of a bayonet-joint, so as to permit it to be easily removed and be replaced by a new support. This interchangeability renders the support independent of the lamp, which offers certain advantages, as the support may be easily removed for repairing. From the tubular support *g* depend supporting-rods *h*, which carry a capsule *i*, which is provided with a baffle-plate *l*. The tubular support is also provided with hooks *s*, on which the mantle *r* is hung. The air for aiding the combustion of the flame enters at the upper and lower parts of the globe *n*, flowing through openings *e*, situated in the portion *m* of the lamp and also either at the lower end of the glass globe *n*, as shown in Fig. 1, or somewhere in the surface thereof, as shown in Fig. 3. Ornamental shades *o* may be employed to increase the similarity to electric lamps. The regulation of the gas-supply entering the mixing-chamber is effected by means of valves, regulating-cocks, screws, and the like in the usual manner.

In the modification shown in Fig. 3 the supply-valve is operated by a rod *p*, which terminates in a milled head *q* for conveniently turning the same.

The action of the device is as follows: The current of mixed gas and air emerges from the tube *f* and flows against the baffle-plate *l*, by which it is deflected and caused to flow radially toward the circumference of the baffle-plate and against the mantle which overhangs it, whereby the same is uniformly enveloped from all sides by the mixture.

The capsule *i* and the baffle-plate *l* are preferably made of transparent material, such as glass, mica, and the like, for avoiding as much as possible the formation of shadows underneath the lamp.

Should it be desired to protect the lamp in a more thorough manner against external influences, in particular against drafts, the downwardly-flowing gas is so guided that instead of at once issuing into the opening at the lower part of the tube *f*, as shown in Fig. 1, it passes down an extension-tube *z* and is guided thereby to the baffle-plate *l*, as shown in Fig. 4.

In order to increase the similarity of appearance of this lamp to electric lamps the gas may be supplied through hollow chains, similar to those shown in Fig. 4, and to those 5 generally used for supporting electric lamps. The individual chain-links *x* communicate with each other, while the top link of the chain communicates with the hollow hook *y*, which in turn is connected with the gas-supply tube. For the purpose of easily adjusting the mantle the tube *z* is screw-threaded, while the tubular support *t*, which is provided with hooks *s*, is also screw-threaded, and so adapted to be moved up and down.

15 Having thus described my invention, I claim as new and desire to secure by Letters Patent—

1. An incandescent gas-burner of the inverted type, comprising a supply-tube, a gas 20 and air mixing chamber, an incandescent mantle, a tubular support at one end of the mixing-chamber for supporting the incandescent mantle, and a baffle-plate supported at the lower end of the mantle for deflecting the 25 mixture of gas and air against the sides of the incandescent mantle, substantially as set forth.

2. An incandescent gas-burner of the inverted type, comprising a supply-tube, a gas 30 and air mixing chamber, a tube at one end of the mixing-chamber, an incandescent mantle, a tubular support removably connected with 35 said tube, hooks on said tubular support for supporting the incandescent mantle, and a baffle-plate supported at the lower end of the mantle for deflecting the mixture of gas and air against the sides of the incandescent mantle, substantially as set forth.

3. An incandescent gas-burner of the inverted type, comprising a supply-tube, a gas 40 and air mixing chamber, an incandescent mantle, a tubular support at one end of the mixing-chamber for supporting the incandescent mantle, a baffle-plate supported at the lower end of the incandescent mantle for deflecting the mixture of gas and air against the sides of the mantle, and means for raising or lowering the tubular support, substantially as set forth.

4. An incandescent gas-burner of the inverted type, comprising a supply-tube, a gas 50 and air mixing chamber, an incandescent mantle, a tubular support at one end of the mixing-chamber provided with means for supporting an incandescent mantle, a transparent capsule supported at the lower end of the mantle, and a baffle-plate in said capsule, 55 substantially as set forth.

5. An incandescent gas-burner of the inverted type, comprising a supply-tube, a gas 60 and air mixing chamber, an incandescent mantle, a tubular support at one end of the mixing-chamber for supporting an incandescent mantle, an extension-tube on said tubular support, and a baffle-plate at the lower 65 end of the extension-tube, substantially as set forth.

In testimony that I claim the foregoing as my invention I have signed my name in presence of three subscribing witnesses.

ADOLF BACHNER.
